CLAIM

The ornamental design for a long bar handle, as shown and described.

DESCRIPTION

FIG. 1 is an isometric view of a long bar handle with cut away portions showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an isometric view of an alternative of long bar handle with cut away portions and center portion thereof;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is an isometric view of the long bar handle of FIG. 8 without cutaway portions.
